(57) **CLAIM**

I claim, the ornamental design for a biopsy device for medical use, as shown and described.

DESCRIPTION

1. Biopsy device for medical use

1.1 : Perspective

1.2 : Front

1.3 : Back

1.4 : Left

1.5 : Right

1.6 : Top

1.7 : Bottom

1 Claim, 7 Drawing Sheets(56)
